MEANS FOR HUMIDIFYING OXYGEN

Jay A. Heidbrink, Minneapolis, and Clinton G. Herrick, Hopkins, Minn., assignors to Air Reduction Company, Incorporated, New York, N. Y., a corporation of New York

Application October 5, 1944, Serial No. 557,310

3 Claims. (Cl. 261—21)

1

Our invention relates to means for humidifying oxygen as the same is delivered to a nasal catheter in use, and has for its object to provide instrumentalities which will operate in connection with the delivery of oxygen to and through a nasal catheter for completely saturating with water the oxygen as delivered, or even for producing a plus saturation.

Because a nasal catheter necessarily embodies a passage of small diameter, the delivery portion is extended as much as the space in the nasal passage will permit with numerous small side openings, and to get the requisite amount of oxygen it must be delivered under such pressures that jets of oxygen traveling at high velocity will be caused to impinge upon the tissues of the pharynx. The effect of this is to dry out excessively the tissues so impinged producing a condition which induces at the least a grave discomfort to the patient. Yet giving oxygen by a catheter to bedridden patients is often the only practical means or the means considered desirable for the administration of oxygen.

As now practiced, it is customary to conduct the oxygen gas, in its travel to the catheter, to the bottom of a body of water held in the container, so the oxygen bubbles up through the water and thereafter passes on to the catheter. Although this practice effects some degree of humidification, it produces at best only partial saturation of the stream of oxygen delivered through the catheter.

We have discovered that by using oxygen at determined high pressure and delivering it in a small jet, which, because of the high pressure moves with a high velocity, and by causing a stream or streams of water to be injected into the path of the jet, and thereafter freeing the moving oxygen from unvaporized water, complete water saturation or even a plus saturation of oxygen received by the patient may be effected. When so humidified, even though the oxygen jets do strike the tissues with a great deal of speed, there will not be any discomforting drying because the oxygen already carries its maximum absorptive amount of water vapor. Hence, as would be expected, the use of such water-saturated oxygen given by a catheter does not produce injurious or discomforting drying effects in its administration by and through the nasal catheter.

We have also discovered that where a single jet of oxygen is delivered from a high pressure oxygen tank into a tube, at pressures such that the delivery from the catheter produces a jet of oxy-

2

gen of high velocity, a degree of vacuum will be produced thereby in the tube or chamber through which the oxygen passes, and if a stream of water is caused by this vacuum to impinge upon the high velocity oxygen jet, the water will not only be atomized in the tube, but water vapor will be absorbed in the oxygen gas in sufficient quantities to completely saturate it.

We also have discovered that if the water stream across the jet of oxygen be broken into a fine spray, as by being drawn from bubbles in a chamber surrounding but communicating with the vacuum chamber within the jet tube, a higher degree of efficiency in effecting oxygen humidification is thereby obtained.

Such saturated oxygen gas can then be forced by its pressure in the humidifying chamber to and through the openings in the catheter, where, although impinging upon tissues at high speed, no serious or discomforting drying effect results, because the gas already has absorbed its maximum possible amount of water vapor.

It is a principal object of our invention, therefore, to control the movement of oxygen gas from a tank or other source thereof at high pressure so that the gas will be delivered in a small jet moving at high velocity within a jet tube, a degree of vacuum therein being caused by the moving jet, and to bring a stream of water or water and gas into said tube through the vacuum action therein so that the water will cross the path of the jet, whereby the oxygen gas will be completely saturated with water vapor.

It is a further object of our invention to deliver the jet of oxygen vertically downward into a tube having its open lower end above the surface of water held therebeneath, and to carry a second tube of small internal diameter from toward the bottom of said water to a point at right angles to and immediately adjacent the outer limits of said jet where it is traveling at substantially its highest speed, whereby the vacuum formed in the first tube by the jet will cause water to be drawn up through the second named and small tube so a stream thereof will be thrown across the line of movement of the jet and thereby the water will be finely atomized with a predetermined volume of gas drawn in by the vacuum caused by the jet, to effect complete saturation of the oxygen gas before it is delivered to the catheter and the patient.

It is a further object of our invention to form a closed chamber about the jet tube except for openings thereinto from the space above the water in the chamber below the jet tube, and to

form a series of openings in the horizontal plane of water delivery across the jet, whereby large volumes of gas are continually drawn into the jet tube along the plane of and about the point of delivery of water across the jet.

It is a further object of our invention to shape the inside of the jet tube with a Venturi opening at the central part and an expanded portion at the upper part and with a multiplicity of openings through the walls of the expanded portion, and to extend a water tube of small bore through the tube wall to a point adjacent the center of the tube, and to control delivery of high pressure oxygen so that a jet thereof is moved at high velocity through the center of said expanded portion and through the venturi and discharged upon a guard plate beyond the open lower end of the jet tube; and to provide a multiplicity of openings of large combined area into the chamber about the jet tube, to cause oxygen to be drawn in through the openings and the whole mixture to be driven upon a guard plate from which it is recirculated again and again, and the gas is completely saturated with water vapor before being forced from the apparatus to the delivery means conveying it to the catheter.

It is a further object of our invention to provide a bell chamber about the vacuum tube, with a small tube connection to near the bottom of the water container, vacuum from the vacuum tube causing water to bubble to a determined level in the bell chamber, and to run a water delivery pipe from below said level to a point close to the gas jet in the vacuum tube.

The full objects and advantages of our invention will now be pointed out in the following detailed specification, and its novel features by which the above noted advantages are attained will be particularly pointed out in the claims.

In the drawings, Fig. 1 is a side elevation view of an embodiment of our invention showing connections therefrom to the oxygen tank and the catheter respectively. Fig. 2 indicates somewhat diagrammatically a source of oxygen stored under high pressure adapted to be put into communication with our humidifying apparatus. Fig. 3 is a sectional elevation view taken on line 3—3 of Fig. 4. Fig. 4 is a sectional plan view taken on line 4—4 of Fig. 3. Fig. 5 is a sectional plan view taken on line 5—5 of Fig. 3. Fig. 6 is a sectional elevation view of a modified form of our invention. Fig. 7 is a sectional plan view taken on line 1—7 of Fig. 6. Fig. 8 is a sectional plan view taken on line 8—8 of Fig. 6.

A cylindrical member 10 which may be formed of glass, plastic, or other transparent material, has its top edge 11 contacting a gasket 12 which fits upon a seat 13 inside of an annular outside flange 14 of a cap piece 15. The lower edge 16 of cylinder 10 rests upon an annular gasket 17 which in turn rests upon a surface of a partition member 18 formed in conjunction with a rim 19, the upper part of which surrounds and engages the lower part of cylinder 10.

The cap piece 15 is provided with an internally threaded boss 20. A tube 21, which will be referred to herein either as a jet tube or a vacuum tube, is formed to provide an upper cylindrical chamber 22, a reduced central Venturi chamber 23 and a lower expanding chamber 24 which opens from the bottom of the tube at 25. Surrounding the opening 25 is a horizontal flange 26 formed on the tube 21. The upper end of tube 21 is threaded as indicated at 27 and is screwed into the internally threaded boss 20 to bring the

upper edge 28 of tube 21 into the space 29 below an annular horizontal surface 30 at the top of threaded opening in boss 20 and surrounding an externally threaded reduced-diameter chamber 31.

It follows that with the parts in the position shown in Fig. 2 when the cap piece 15 has its internally threaded boss turned down upon the threaded upper end of tube 21, the gaskets 12 at the top and 17 at the bottom will be compressed and an upper chamber assembly will result which includes a chamber 32 having for its bottom the partition 18 and a chamber 33 in the cap piece 15, which chambers are sealed from the outside.

Threaded into the reduced portion 31 is an oxygen delivery member 34 which is provided with a central channel 35 extending into a limit port 36 at the center of its bottom, which limit port is of small diameter, and effective at twenty-one thousandths of an inch, which operates satisfactorily over the range of usual delivery through a catheter.

In a plane slightly below the outlet of limit port 36 are a multiplicity of gas inlet openings 37, Fig. 3, which are adapted to admit oxygen gas to the chamber 22 and within the jet tube 21 when the device is in operation. Also extending through the wall of tube 21 to enter chamber 22 is an end 38 of a small tube 39, which extends through partition 18 to a point near the bottom 40 of a water holding chamber 41 forming a cup-shaped member 42 later to be described.

By means of a connector member 43 and fastening nut 44 the chamber 31 and passageway 35 to limit port 36 are connected to a suitable tubing 45. This tubing is in communication with a gas-receiving member 46 which in turn communicates through tubing 47 with an oxygen tank 48, indicated somewhat diagrammatically in Fig. 2. The receiving chamber 46 is connected with a gauge 49 indicating the pressures at which the oxygen will be delivered to the jet port 36. Both the volume of oxygen delivered and the velocity of the jet will of course depend upon the delivery pressure of the gas, as indicated upon a gauge 48, and this pressure will be determined by operation of tank valve 49, indicated diagrammatically at Fig. 2, which is of usual construction.

The oxygen gas forced through jet tube 21 and opening 25 at the bottom thereof, together with the water driven along with it, will be driven upon guard plate 50 secured to the partition 18 by screws 51. Spacers 52 hold the guard plate spaced a suitable distance, as indicated at 53, from the lower surface of the partition 18. The guard plate 50 is preferably formed of porous metal or metal having therein a multiplicity of fine perforations, and it acts upon the blast of oxygen gas and water driven upon its upper surface to catch and hold any free water moving with the humidified gas. This gas spreads out in the space 53 and flows up into chamber 32 through a multiplicity of openings 54. These openings have a combined area sufficiently great so that the gas will move through them at slow speed and have no tendency to carry up into chamber 32 any particles of free water.

Part of the gas in chamber 32 will be drawn through openings 37 in jet tube 21 by reason of the considerable degree of vacuum produced by the oxygen jet within the tube and particularly within chamber 22 therein. Thus there will be

a very considerable recirculation of the oxygen gas from chamber 32. It also follows that since the oxygen being delivered will quickly fill the chamber 32 and any open space within chamber 41, its pressure will build up to a considerable part of the delivery pressure until the gas will be forced from the chamber 32. It passes through a channel 55 formed in an extension 56 of the cap piece 15. The channel 55 opens at 57 into the chamber 33 in the top of cap piece 15 in direct communication with chamber 32. At its other end the channel 55 communicates with a channel 58 through a connector member 59, Fig. 3, which in turn is connected with a tube 60 leading to the catheter 61, Fig. 1.

The cup-shaped member 42 has a cylindrical wall 62 the upper edges of which are forced against a gasket 63 held within an annular flange 64 on the bottom of partition 18. This cup-shaped member is removably held by a yoke member 65, which has its upper ends 66 and 67 of its side arms provided with screw trunnions 68 and 69 situated in trunnion sockets 70 and 71 and held in position by lock nuts 72 and 73. A thumb screw 74 is threaded through a boss 75 in the central part of yoke member 65 and engages with its end 76 a depression 77 in the bottom wall 40 of cup member 42.

This arrangement enables the cup member 42 to be easily removed and replaced. The chamber 41 is designed to hold a suitable supply of water, and no other means of filling this chamber is provided except to remove the cup. It follows that an excess amount of water can not be introduced into the system. Furthermore, any level of water which is provided by attachment of the normally filled cup 42 to the entire apparatus would be immediately lowered by drawing up of water through the tube 39 by reason of the vacuum formed in the chambers within the jet tube 21 so that the maximum level of water in chamber 41 could not be higher than that indicated at 78 in Fig. 3.

The tube 39 has its bottom 79 adjacent the bottom 40 of chamber 41. The vacuum in chamber 22 and the other chambers of jet tube 21 will cause water to flow through this tube, be atomized and vaporized in the chambers of the jet tube and to continually circulate until the level of the water in chamber 41 approaches or reaches the bottom 79 of tube 39, when the cup member 42 must be removed and a fresh supply of water provided.

In the modified form shown in Figs. 6, 7 and 8, in place of the Venturi vacuum tube 21 within chamber 32 we provide a simple tube 80 connected in the apparatus otherwise exactly as tube 21. Upon partition 18 is formed an annular flange 81 which surrounds the bottom of a bell-shaped member 82 in chamber 32. This member surrounds at 83 the threaded upper end 84 of the tube 80 and engages with its lower annular face 85 a gasket 86 resting on the partition 18 inside of flange 81, thus forming a second chamber 87. Openings 88 are formed through the partition 18 into the chamber 87, these openings being proportioned in size and number to give a suitable inflow of gas to the interior of tube 80.

Formed in connection with a block 89 is a tube 70, Figs. 6 and 7, which discharges at 91 directly across the line of the gas jet from opening 36. Through block 89 is a passageway 92 which leads into the chamber 87 and connects with the tube passage 90. A second opening and passageway 75

93 turns downwardly and connects with the tube passageway 90 and also with a downwardly-extending tube 94 which terminates at 95 toward the lower part of the chamber 87. A second tube 96 opens through partition 18 into chamber 87 and extends to a point 97 near the bottom of a water chamber 41.

The effect of the use of these parts is that the gas jet from the gas opening 36 driving across the opening 91 of tube 90 produces a degree of vacuum in tube 90 which at the same time draws gas through opening 92. This produces a degree of vacuum in chamber 87 and draws spray and gas through tube 94. The vacuum in chamber 87 causes water to be drawn through tube 96 and bubbles of gas to pass through openings 88. The maximum area of openings 88 in relation to water delivery tube 96, to gas inlet 92 and water delivery through tube 90 is such as to cause tube 96 to maintain a bubbling mass of liquid 98 in chamber 87 with a level substantially as indicated at 99 and which will surround the opening 95 of tube 94.

Hence, the gas drawn through tube 94 will carry with it a spray of water which is carried out of opening 91 into the gas jet from jet opening 36 and which there is atomized and forced downward through the open end of tube 80 upon guard plate 50, resulting very effectively in a complete humidification. This highly humidified gas will in turn, some part of it, be recirculated through openings 88 and chamber 87 with the result that the gas which finally leaves chamber 32 to go to the catheter has an excess humidification such that as the gas warms on its journey to the catheter it will maintain substantially 100% humidification at the point of delivery from the catheter.

As shown in Fig. 6 the bell casing 82 is formed of transparent material such as glass or transparent plastic or the like, and likewise the wall 10 will be of transparent material. This permits a view of the bubbling taking place in chamber 87, which has the advantage of informing the operator that the gas is in fact going through.

Level 99 of liquid within the chamber 87, as shown in Fig. 6, is of course not a fixed level, but a boiling mass with bubbles going through from the openings 88 in partition 18. However, the relation between the opening 96, the air inlet opening 92 and the aggregate area of openings 88 is such that bubbling water will rise in chamber 87 to a point above the opening 95 of tube 94. But then the flow of water through the tube 94 and into the jet tube 80 will be such as to maintain the bubbling mass 98 substantially at a constant height.

The advantages of our invention as heretofore indicated grow out of its simplicity of construction and its high efficiency in delivering oxygen to a catheter which is completely saturated with water vapor. One of the important advantages also comes from the fact that the delivery of oxygen itself creates the vacuum which causes water to be drawn through the tube 39 from the supply in the receptacle and said water to be injected from the transversely extended nozzle 38 in a stream directly across the high velocity jet of oxygen gas, which results in atomizing the water.

Other advantages come from the fact that this atomizing of water takes place at the center of a set of streams of gas pouring in from the surrounding chamber to fill the vacuum caused by the jet, and that these streams of gas cause the

entire oxygen content of the superposed chambers in the apparatus to be repeatedly subjected to vaporized water so that the absorption of water vapor ultimately completely saturates the oxygen gas. Indeed, tests tend to show that there is more than 100% saturation of the gas with true water vapor at the temperature within the chamber, so the gas is completely saturated at the somewhat higher temperature of delivery to the patient.

We claim:

1. An apparatus for effecting saturation of oxygen with water vapor as it is delivered to a nasal catheter, comprising a casing, a partition dividing the casing into upper and lower chambers, the lower chamber adapted to hold a supply of water, a jet tube extending through the upper chamber and opening into the lower chamber, a source of oxygen under pressure and means controlling the flow of that oxygen to cause a high velocity jet thereof to be delivered downwardly along the tube, a bell chamber surrounding the jet tube, a water pipe having a delivery nozzle in the tube adjacent the air jet and having a lateral opening into the bell chamber and having a downwardly turned end toward the partition, a second water pipe extending through the partition to a point near the bottom of the lower chamber in the body of water therein, and a multiplicity of apertures through the partition and into the bell chamber so proportioned in aggregate area that the vacuum created in the bell chamber by the jet will cause water to enter the lower part of the bell chamber and bubble about the lower end of the first-named water pipe to be delivered therethrough in a spray across the gas jet.

2. An apparatus for effecting saturation of oxygen with water vapor as it is delivered to a nasal catheter, comprising a casing, a partition dividing the casing into upper and lower chambers, the lower chamber adapted to hold a supply of water, a jet tube extending through the partition and across the upper chamber and a source of oxygen under pressure and means controlling the flow of oxygen to cause a gas jet to be delivered downwardly within the jet tube and into the

water chamber, means on the partition forming a bell chamber surrounding the jet tube above the partition, said partition having an opening providing communication between the water-holding chamber and the bell chamber, a vertical pipe with an open lower end and a horizontal pipe connected to the first pipe extending into the jet tube, said horizontal pipe having an open end adjacent the gas jet in the jet tube, and having its opposite end open within the bell chamber, and water conveying means extending from the water chamber into the bell chamber, whereby the vacuum formed in the jet tube will be transmitted into the bell chamber to cause water to be drawn thereinto through the conveying means and to cause gas to be drawn through the opening in the partition to bubble through the water and to cause gas and water to be drawn through the pipe and to be injected into and across the oxygen jet whereby the water is atomized and caused to circulate and to vaporize in the oxygen delivered by the jet.

3. An apparatus for effecting saturation of oxygen with water vapor as it is delivered to a nasal catheter, in accordance with claim 2, wherein there is a guard plate supported beneath and in spaced relation to the partition to catch and hold free water and to spread the gas into the upper portion of the water chamber.
